U.S. PATENT DOCUMENTS

The ornamental design of a support rail assembly for office accessories, as shown and described.

DESCRIPTION

401,553 A 4/1889 Godfrey
 1,039,554 A 9/1912 Lindhorst
 1,830,347 A 11/1931 Camden et al.
 2,551,157 A 5/1951 Price
 2,979,155 A 4/1961 Scharfenberger
 D239,896 S 5/1976 Bortcher
 4,126,230 A 11/1978 Tyson et al.
 4,317,416 A 3/1982 Baum et al.
 4,323,291 A 4/1982 Ball
 4,709,891 A 12/1987 Barnett
 4,852,500 A 8/1989 Ryburg et al.
 4,869,378 A 9/1989 Miller
 4,879,955 A 11/1989 Moll et al.
 4,884,513 A 12/1989 Newhouse et al.

FIG. 1 is a front perspective view of the support rail assembly for office accessories embodying our design, the rear edge portion of a worksurface being shown in dotted lines as environment and forming no part of the claimed design;

FIG. 2 is a top view thereof;

FIG. 3 is a bottom view thereof;

FIG. 4 is a left side view thereof; the right side view being a mirror image thereof;

FIG. 5 is a front view thereof;

FIG. 6 is a rear view thereof; and,

FIG. 7 is an enlarged cross-sectional view taken generally along line 7—7 in FIG. 1.

1 Claim, 6 Drawing Sheets
